UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,196,661.

Specification of Letters Patent. Patented Aug. 29, 1916.

Application filed October 31, 1912. Serial No. 728,852.

To all whom it may concern:

Be it known that I, JOHN E. CHALMAN, a citizen of the United States, residing at Chicago, in the county of Cook, State of Illinois, have invented certain new and useful Improvements in Presser-Feet for Sewing-Machines, of which the following is a description, reference being had to the accompanying drawing and to the figures of reference marked thereon.

The invention relates to new and useful improvements in presser feet for sewing machines, and more particularly to a presser foot which is adapted for use in connection with a multiple needle sewing machine, wherein certain of the needles are widely spaced.

An object of the invention is to provide a presser foot of the above character, which is so supported by the presser foot supporting means that the foot portion may tilt laterally, so as to accommodate extra thicknesses of material at one side of the presser foot, and which presser foot is also provided with adjustable means for limiting the tilting action of the foot portion.

A further object of the invention is to provide a presser foot of the above character with an auxiliary yielding foot portion, or section, which is carried by the tilting main foot portion of the presser foot, and which may yield or move relative to said main foot portion, whereby extra thicknesses of material may be accommodated at certain portions of the presser foot, without disturbing the position of the main portion of the presser foot relative to the material.

These and other objects will in part be obvious and will in part be hereinafter more fully disclosed.

In the drawings, which show by way of illustration, one embodiment of the invention, Figure 1 is a side view of a presser foot embodying my invention; Fig. 2 is a rear view of the same; Fig. 3 is a top plan view of the same; Fig. 4 is a plan view of the main foot portion and the auxiliary foot portion showing the supporting shanks therefor in section; Fig. 5 is a longitudinal sectional view through the supporting bracket for the auxiliary presser foot, and also through the main portion of the presser foot; Fig. 6 is a detail showing the hinged connection between the main presser foot

and the supporting shank; Fig. 7 is a diagrammatic view showing the use of my improved presser foot, and the relation of the various parts to the fabric when uniting a single piece plait to the body fabric. Fig. 8 is a detail showing modified form of fabric guide. Fig. 9 is a transverse section of the same.

In carrying out the invention, I have provided a presser foot which consists of a main portion 1. This main portion 1 has an upwardly extending lug 2, which is perforated to receive a pivot screw 3. The pivot screw 3 passes through the forked lower end of the supporting shank 4, of the presser foot. This pivot screw is located longitudinally of the presser foot, so that said presser foot is capable of yielding or tilting laterally or transversely of the line of feed. Said main presser foot, as shown in the drawings, is especially adapted for use in connection with a multiple needle sewing machine. The presser foot is extended laterally so as to engage the fabric operated upon by each of the needles. As illustrated in the drawing, said foot is adapted for a four-needle machine, wherein the needles are arranged in pairs and at points adjacent the lateral edges of said presser foot. Said presser foot is provided with slots 5 and 6, through which the needles pass during the stitching operation.

The main presser foot is turned upwardly at its forward end, as at 7. Fabric guides 8 are adjustably attached by screws 9, 9 at each side of the presser foot. These guiding members project forwardly from the foot and extend downwardly to the lower surface of the presser foot. In stitching a plait to a body fabric, the folded strip is guided by these guiding members 8, 8. In Fig. 7 of the drawing, I have shown diagrammatically a folded plait P which is being stitched to a body fabric B. This folded plait is passed underneath the main part of the presser foot, so that the needles 100 passing through the slots 5, 5 will pass through the folded plait adjacent to the edge thereof, while the needles passing through the slots 6 at the other side of the presser foot will pass through the folded edges of the plait. As shown in the drawing, the plait is folded so that the inner needle passes through the lower part of the

folded plait, and the body fabric, while the outer needle passes through the upper part of the folded strip and body fabric only. It will thus be apparent that at the 5 folded edges of the plait, the inner needle is passing through five thicknesses of fabric, while the outer needle is passing through three thicknesses of fabric. The needles entering the slots 5, 5 are passed through 10 only two thicknesses of fabric.

As above noted, the main part of the 15 presser foot is secured to a shank so that it can tilt laterally. This allows the main foot to tilt so as to accommodate the varying thicknesses of the fabric at the two side edges of the foot. In order that the tilting movement of the main portion of the foot may be limited, I have provided the supporting shank 4 with an outwardly projecting arm 10, which is formed with a split collar 11, at its outer end, in which is located a threaded screw 12. The edges of the split collar are joined by a screw 13. This screw 12 may be adjusted in the arm 10 20 and is held in adjusted positions by the screw 13. The upward movement of the side of the presser foot having the slots 6 will, therefore, be limited by this adjustable screw 12.

30 The main portion of the presser foot 1 is cut away so as to form a space or recess 14, which extends from front to rear of the presser foot. Located in said recess or space 14 is an auxiliary presser foot 15, which 35 is mounted on a shank 16, adapted to slide in a bracket 17, which spans said recess or space 14, and is attached to the main portion of the presser foot 1. As clearly shown in Fig. 5, this recess extends entirely to the 40 front receiving portion of the presser foot, so that if said auxiliary presser foot is raised, as shown in dotted lines in said figure, the fabric is free to pass underneath said auxiliary presser foot, which will engage the same without coming in contact with the main portion of the foot. This auxiliary presser foot 15 is yieldingly pressed downward, so that its lower surface is normally flush with the lower surface of 45 the main portion of the presser foot, by a spring 18. A second bracket 19 is secured to the bracket 17 and said spring 18 extends horizontally, and is then coiled and extended vertically, where it is secured to 50 said second bracket by a screw 20. A screw 21 passing through the bracket 19 presses against the spring, and may be used for varying the tension thereof. The downward movement of the shank 16 of the auxiliary 55 presser foot is limited by a pin 22, which extends through said shank and is adapted to bear against the upper face of the bracket 17. As clearly shown in the drawing, the bracket 17 is spaced above the upper face 60 of the main portion of the presser foot 1 so

that said auxiliary presser foot has a limited range of movement underneath the bracket. The recess 14 and auxiliary presser foot 15 are so positioned that said auxiliary presser foot engages the plait being stitched to the 70 body fabric directly over that part of the plait having the increased thickness. That is to say, the auxiliary presser foot bears on the five layers of the fabric, and will yield so that the plait will be properly held for 75 stitching, and evenly fed to the stitching mechanism, notwithstanding the great width of the plait.

In Fig. 8 of the drawing, I have shown a slightly modified form of fabric guide for 80 guiding the edge of the plait being stitched to the body garment. These guides, indicated at 8^a, are extended underneath the foot, as shown at 8^b, to the rear edge thereof. These guides are located outside the needle 85 openings and guide the edge of the plait, as above noted.

The arm 10 extending laterally from the main shank of the presser foot, carries an adjustable means, which not only serves to limit the tilting movement of the main foot, but also regulates the pressure of the main foot, where the plurality of thicknesses passes underneath the same against the fabric. That is to say, the uneven thickness 95 of the plait will cause the foot to tilt. By adjusting said screw the pressure of the foot against the folded-in edges of the plait may be made greater than the pressure of the foot at the opposite side thereof, where the plait is of less thickness. This added pressure or varying pressure on the pivoted foot portion enables the fabric to be evenly fed to the stitching mechanism, regardless of the varying thickness at different parts therein. 100

105 It is obvious that minor changes in the details of construction, and the arrangement of parts may be made without departing from the spirit of the invention, as set forth in the appended claims.

110 Having thus described my invention, what I claim is:—

115 1. A presser foot for sewing machines comprising a shank, a foot portion pivoted thereto so as to tilt laterally, an auxiliary foot portion carried by said main foot portion, and means for yieldingly supporting said auxiliary foot portion.

120 2. A presser foot for sewing machines comprising a shank, a foot portion pivoted thereto so as to tilt laterally, said foot portion having a recess formed therein extending from the front to rear, an auxiliary presser foot located in said recess, and means for yieldingly supporting said auxiliary foot portion from said main foot portion, whereby said auxiliary foot portion may yield vertically and tilt with said main foot portion.

125 3. A presser foot for sewing machines,

comprising a shank, a foot portion pivoted thereto, so as to tilt laterally, said foot portion having a recess formed therein from front to rear, a bracket carried by the main foot portion and spanning said recess, an auxiliary foot portion supported by said bracket so as to yield vertically, said auxiliary foot portion being located in said recess.

4. A presser foot for sewing machines comprising a shank, a foot portion pivoted thereto so as to tilt laterally, means for limiting the tilting movement of said presser foot, said presser foot having a recess extending from front to rear, an auxiliary presser foot located in said recess, and means for yieldingly supporting said auxiliary presser foot from said main foot portion, whereby said auxiliary presser foot may tilt with said main foot portion.
5. A presser foot for sewing machines, comprising a shank, a foot portion pivoted thereto, so as to tilt laterally, and having a recess formed from front to rear, an auxiliary foot portion located in said recess, a bracket carried by the main foot portion, and spanning said recess, a shank carried by said auxiliary portion and adapted to slide vertically in said bracket, means for limiting the downward movement of said auxiliary foot portion, and a spring for yieldingly holding said auxiliary presser foot, with its lower surface flush with the lower surface of said main foot support.

6. A presser foot for sewing machines, comprising a shank, a main foot portion pivoted thereto, so as to tilt laterally, an arm carried by said shank, a screw adjustably secured in said arm and adapted to engage said foot portion for limiting the tilting movement thereof, said main foot portion having a recess formed therein from front to rear, an auxiliary presser foot located in said recess, and means for supporting said auxiliary presser foot, from said main foot portion, whereby said auxiliary presser foot will tilt with the main foot portion.

7. A presser foot for sewing machines, comprising a shank, a body portion pivoted thereto so as to tilt laterally, and an auxiliary foot portion carried by said main body portion, said auxiliary foot portion being located in a space formed in said main body portion.

8. A presser foot for sewing machines comprising a shank, a foot portion pivoted thereto so as to tilt laterally, an auxiliary foot portion supported by said shank, and a third portion carried by said shank and engaging said main portion.

9. A presser foot for sewing machines comprising a shank, a main body portion pivoted thereto, an arm attached to the shank and an adjustable member carried by said arm for engaging said main body por-

tion, whereby the pressure of said main body portion on the material may be varied at the side thereof adjacent said member.

10. A presser foot for sewing machines comprising a shank, a main body portion pivoted thereto, an auxiliary portion carried by said main body portion, an arm attached to said shank, and an adjustable member carried by said arm and adapted to engage said main body portion, whereby the side pressure of the main body portion can be varied.

11. A presser foot for sewing machines comprising a shank, a main foot portion pivoted thereto, an auxiliary portion, means for yieldingly supporting said auxiliary portion independently of said main portion, and means for limiting the tilting movement of said main portion.

12. A presser foot for sewing machines comprising a shank, a main foot portion, an auxiliary foot portion, means for supporting said auxiliary foot portion, whereby it will yield vertically independently of said main foot portion, means to regulate the pressure of said auxiliary foot portion, and means whereby said main foot portion may be tilted and held in tilted position.

13. A presser foot for sewing machines comprising a shank, a main foot portion, an auxiliary foot portion, means for supporting said auxiliary foot portion, whereby it will yield vertically independently of said main foot portion, means to regulate the pressure of said auxiliary foot portion, means whereby said main foot portion may be tilted and held in tilted position, and means for limiting the downward movement of said auxiliary foot portion.

14. A presser foot for sewing machines comprising a shank, a main foot portion having a recess located between the sides thereof, said recess being closed at the front end thereof by the up-turned portion of said main foot, means for supporting said main foot portion, whereby it may rock sidewise, an auxiliary foot portion located in said recess, said upturned portion of the main foot operating to direct the material underneath said auxiliary foot portion, and means for supporting said auxiliary foot portion, whereby the same is rocked with the main foot portion.

15. A presser foot for sewing machines comprising a shank, a main foot portion, an auxiliary foot portion, means for pivotally supporting said main foot portion by said shank, means for supporting said auxiliary foot portion by said main foot portion, a member located above the pivotal connection between said main foot portion and said shank and supported by said shank, acting on said main foot portion for limiting the movement thereof above said pivotal point, said means for supporting said auxiliary

foot portion including devices whereby said auxiliary foot portion may yield vertically independently of said main foot portion.

16. A presser foot for sewing machines comprising a shank, a main foot portion having a recess, an auxiliary foot portion located in said recess, means whereby said auxiliary foot portion is supported so as to yield vertically independently of said main foot portion, said means including an arm attached to said main foot portion, and ex-

tending over said recess above the main foot for supporting said auxiliary foot portion, whereby the same may move vertically relative to said main foot portion.

In testimony whereof, I affix my signature in the presence of two witnesses.
